CLAIM

The ornamental design for a subtalar arthroereisis implant, as shown and described.

DESCRIPTION

FIG. 1 is a perspective view of the subtalar arthroereisis implant showing our new design;

FIG. 2 is a top plan view thereof;

FIG. 3 is a bottom plan view thereof;

FIG. 4 is a right side elevational view thereof, the left side being identical; and

FIG. 5 is a front elevational view thereof, with the rear elevational view being identical.
